US0D1091209S

(12) **United States Design Patent** (10) **Patent No.:** **US D1,091,209 S**
(45) **Date of Patent:** **** Sep. 2, 2025**

(54) **DRINKING STRAW**

(71) Applicant: **Igloo Products Corp.**, Katy, TX (US)

(72) Inventors: **Haley Bodziak**, Huntington Beach, CA (US); **James Ira McKenrick**, Katy, TX (US)

(73) Assignee: **Igloo Products Corp.**, Katy, TX (US)

(**) Term: **15 Years**

(21) Appl. No.: **29/880,022**

(22) Filed: **Jul. 17, 2023**

(51) **LOC (15) Cl.** **07-06**

(52) **U.S. Cl.**

USPC **D7/300.2**

(58) **Field of Classification Search**

(57) **CLAIM**

The ornamental design for a drinking straw as shown and described.

DESCRIPTION

FIG. 1 is a first perspective view of a design of a drinking straw;

FIG. 2 is a second perspective view of the design of FIG. 1;

FIG. 3 is a front view of the design of FIG. 1;

FIG. 4 is a rear view of the design of FIG. 1;

FIG. 5 is a first side view of the design of FIG. 1;

FIG. 6 is a second side view of the design of FIG. 1;

FIG. 7 is a top view of the design of FIG. 1;

FIG. 8 is a bottom view of the design of FIG. 1; and,

FIG. 9 is a perspective view of the design of FIG. 1 in a disconnected configuration.

1 Claim, 9 Drawing Sheets
